(57) **CLAIM**

The ornamental design for a retractor/depressor, as shown and described.

DESCRIPTION

FIG. 1 is a front perspective view of a retractor/depressor. FIG. 2 is a front view of the retractor/depressor of FIG. 1. FIG. 3 is a sectional side view of the retractor/depressor of FIG. 1.

FIG. 4 is a front perspective view of the retractor/depressor of FIG. 1; and,

FIG. 5 is a rear perspective view of the retractor/depressor of FIG. 1.

The broken lines in the drawings show environmental subject matter that forms no part of the claimed design.
